(57) CLAIM

We claim the ornamental design for a table, as shown and described.

DESCRIPTION

FIG. 1 is a top perspective view of a table showing my new design.

FIG. 2 is a bottom perspective view of the table of FIG. 1. FIG. 3 is an alternate bottom perspective view of the table of FIG. 1.

FIG. 4 is a top view of the table of FIG. 1.

FIG. 5 is a bottom view of the table of FIG. 1.

FIG. 6 is a front view of the table of FIG. 1.

FIG. 7 is a back view of the table of FIG. 1.

FIG. 8 is a side view of the table of FIG. 1; and,

FIG. 9 is a opposite side view of the table of FIG. 1.
